UNITED STATES PATENT OFFICE.

HOWARD G. HODGKINS, OF CHICAGO, ILLINOIS.

STEEL BUILDING CONSTRUCTION.

SPECIFICATION forming part of Letters Patent No. 761,297, dated May 31, 1904.

Application filed July 15, 1903. Serial No. 165,541. (No model.)

To all whom it may concern:

Be it known that I, HOWARD G. HODGKINS, of Chicago, in the county of Cook and State of Illinois, have invented certain new and useful Improvements in Steel Building Construction; and I do hereby declare that the following is a full, clear, and exact description thereof, reference being had to the accompanying drawings, and to the letters of reference marked thereon, which form a part of this specification.

This invention relates to improvements in floor - frame constructions for steel - frame buildings and also to improvements in the general structure of the frames of such buildings; and the invention consists in the matters hereinafter set forth, and more particularly pointed out in the appended claims.

In the drawings, Figure 1 is a broken plan view of a part of one floor structure of a building and a portion of a subjacent floor. Fig. 2 is an enlarged section taken on line 2 2 of Fig. 1.

The construction shown in Fig. 1 is diagrammatical in its nature, the details involving the attachment of the several parts being omitted.

As shown in said drawings, A A designate the supporting posts or columns of the frame structure of the building, and B B the floor-girders extending between and attached to said columns and which support or carry the floor proper, C, of the building.

B' B' designate the outside girders, which in a rectangular building, as is herein illustrated, are arranged at right angles with respect to each other and are joined at the corner of the building.

The columns A are arranged in rows parallel with the side girders B' of the building, said columns being spaced to constitute a plurality of rows which are parallel with the side walls of the building. Said columns are so set that the columns of any group of four occupy the corners of a rectangle, and it is usual to arrange said columns to occupy the corners of an oblong rectangle. The girders B extend between and are attached to the posts A and are arranged diagonally with respect to the sides of the building instead of parallel

therewith. In order to permit the girders to be attached to the columns in the usual manner, said columns, which are herein shown as made of rectangular cross-section, are set diagonally with respect to the side walls of the building or with their side faces parallel with the oblique girders B. The floor proper, C, which is made of concrete, tile, or other fire-proof structure, is bridged or arched across the space between adjacent girders B. As herein shown, said floor C has the form of a flat arch, and the material composing the floor is extended downwardly to cover the sides of said girders, and said downwardly-extending parts rest on the lower flanges of said beams, which are herein shown as made of I-beams. The floor C may be made of any peculiar form of arch desired. The columns A (shown in Fig. 2) are finished columns, which are ordinarily found in a large room of a building—such, for instance, as a store-room or the like—which is not divided into apartments or smaller rooms. For such uses the columns are usually provided with an ornamental finish. The columns of a building which are embedded or inclosed in the walls of building will, however, be only provided with the usual fire-proof cover or protection α , the ornamental feature being omitted.

Heretofore it has been a common practice to arrange the floor-girders parallel with the side walls of the building, and this is an economical plan, so far as the steel structure is concerned, when the columns are spaced so close together as to enable a floor-arch of practical width and depth for a given load capacity to be bridged between two adjacent lines of girders. It often occurs, however, that the rows of posts are set so far apart that the span between two adjacent lines of girders is too great to practically bridge an arch floor between the same to withstand the required floor load with a floor of practical or economical depth or thickness. In cases where the rows of columns are so far apart as to render it impracticable to bridge the span between adjacent girders it has heretofore been a common practice to provide short intermediate beams extending the shorter distance between the adjacent girders and sup-

ported thereon, said intermediate beams being spaced a distance apart to support a practical span of floor for a given or required load stress. This construction, while reducing the 5 span between the adjacent floor-supporting members and enabling a practical floor-arch to safely carry the required load without decreasing the distance between column centers, has the objection of greatly increasing the 10 tonnage of steel required to construct the floor-frame. In other words, the tonnage of steel is increased by that required to supply the transverse beams.

The diagonal arrangement of the girders 15 herein shown is useful in constructions where the rows of columns of the building are set so far apart as to preclude spanning the distance between two adjacent rows of columns with a floor of practical dimensions for a given 20 load and the arrangement is such that while preserving the distance between the column centers the span between adjacent girders is shortened to such extent as to render it practicable to bridge the space between adjacent 25 girders with a floor of practical dimensions for the load required. This advantage is made clear by an inspection of Fig. 1, from which it is evident that the distance between two adjacent obliquely-arranged girders is less than 30 that between the centers of the columns in the shortest direction therebetween. For instance, if the distance between column centers be sixteen feet measured by the shortest distance the distance between the girders arranged obliquely to said rows is approximately 35 twelve feet. The arrangement herein shown permits, therefore, the employment of a single or primary row of girders between which the floor is spanned, while avoiding the necessity 40 of employing the intermediate beams above referred to and yet not exceeding a safe floor-span for the load required. On the other hand, for a given spacing of the columns I am enabled, while maintaining a margin of 45 safety of load stress of the floor, to decrease the thickness of the floor span or arch, with a corresponding reduction in the cost thereof. Furthermore, I may employ a floor of given span and strength while increasing the 50 distance between column centers and may thus be enabled to economize in the cost of the columns. It will therefore be seen that the system of arranging the girders of

the floor structure shown herein results in the saving of steel tonnage when the supporting columns are set so far apart as to preclude the practicability or safety of spanning the distance between said columns, in economizing in the cost of the floor proper notwithstanding the span between adjacent rows of columns, 60 and in economizing in the cost of columns with a given span and strength of floors. 55

As a further and separate improvement the girders of two adjacent floors are arranged at right angles to each other instead of being arranged parallel with each other. This construction is advantageous, as it gives perfect bracing against wind-pressures or the vibration of machinery in the building. In constructing a building of a large number of 70 stories the girders of each two adjacent floors or stories will be arranged in directions at right angles to each other, thereby providing such bracing from the lower to the top stories of the building. 75

I claim as my invention --

1. A steel building-frame comprising columns which are arranged in parallel rows, and floor-girders extending between and supported on said columns, said girders being arranged in parallel rows and all extending in the same direction, and obliquely to the rows of columns, whereby the span between adjacent rows of girders is less than the span between adjacent rows of columns. 80 85

2. A steel building-frame of a number of stories, comprising columns arranged in parallel rows, and floor-girders extending between and supported on said columns, the girders of each floor being arranged in parallel rows and 90 all extending in the same direction, and obliquely to the rows of columns, whereby the span between adjacent rows of girders is less than the span between adjacent rows of columns, and the girders of one floor being arranged transversely with respect to the girders of an adjacent floor. 95

In testimony that I claim the foregoing as my invention I affix my signature, in presence of two witnesses, this 1st day of July, A. D. 100 1903.

HOWARD G. HODGKINS.
